UNITED STATES PATENT OFFICE.

FREDERICK W. SMITH, OF NORTH TONAWANDA, NEW YORK.

ELECTRICALLY-OPERATED VALVE FOR PNEUMATIC MUSICAL INSTRUMENTS.

1,188,851.

Specification of Letters Patent. Patented June 27, 1916.

Application filed June 24, 1915. Serial No. 36,024.

To all whom it may concern:

Be it known that I, FREDERICK W. SMITH, a subject of Great Britain, (who has declared his intention of becoming a citizen 5 of the United States,) residing at North Tonawanda, county of Niagara, and State of New York, have invented certain new and useful Improvements in Electrically-Operated Valves for Pneumatic Musical 10 Instruments, of which the following is a specification.

This invention relates to electrically operated valves for pneumatic musical instruments.

15 My invention relates to that type of electrically operated valve wherein the valve is a disk, under the control of an electro-magnet, and is adapted to control the action of a pneumatic, which in turn, actuates 20 larger valves that control the access of wind pressure of an organ pipe. Valves of this general type normally prevent access of atmospheric pressure to a bellows pneumatic and when attracted by energization of the 25 electro-magnet, uncover a port which lets in atmospheric pressure. As heretofore constructed, this type of electrically operated valve has been subject to the very serious defect that small particles or obstructions 30 are drawn in through the atmospheric port or through the wind chest and lodge on the disk valve or its seat and in the course of time prevent its proper action by keeping it from closely fitting its seat.

35 My object is to provide, in an electrically operated valve of the above-mentioned type, a valve seat and casing of improved construction which will insure accurate and close seating of the disk valve at all times, 40 despite the access of any obstructions or dust particles and which will guide the valve, without the necessity of providing special guiding pins or other devices.

The invention is carried out by the provision, in connection with a disk valve, of 45 a valve casing having a circular recess slightly larger than the valve which serves as a guide therefor and, further, a circular seat which has a sharp edge and a tapered or 50 beveled wall leading from said edge to the shell or casing. The sharp edge of the seat and the beveled wall thereof perform the two-fold function of preventing lodgment of any obstructions or dust particles and of a knife

edge engagement with the disk valve, the 55 latter being preferably provided with a paper or leather facing to cause it to more firmly engage said knife edge seat and to prevent it from adhering to the poles of the 60 electro-magnet.

The invention is set forth fully herein-after and its improved features are recited in the appended claims.

In the accompanying drawings: Figure 1 is a sectional view through a pressure 65 wind chest showing the application of the invention thereto to illustrate its use; Fig. 2, a detail view looking toward the inner face of the outer part of the shell or casing, dotted lines representing the valve; Fig. 3, 70 a detail view looking toward the inner face of the bottom plate, showing the poles of the magnet inserted therein, dotted lines representing the valve; Fig. 4, a longitudinal section through Fig. 2; Fig. 5, a cross section through the valve seat of Fig. 2; Fig. 6, a longitudinal section through the complete valve mechanism, parts of the electro-magnet being broken away; and Fig. 7, a 75 detail of the disk valve.

80 The invention has been shown applied to a pressure wind chest to illustrate its use, but its novelty resides in the features hereinbefore set forth and not in its combination with such wind chest.

85 Referring to Fig. 1, the numeral 1 represents a pressure wind chest from which lead passages, of which only one, 2, is shown, to the organ pipes. Valves 3 and 4 carried by a stem 5 and operated by a bellows pneumatic 6 contained within the chamber 1, constitute the means for controlling the access of pressure to passage 2. The electrically operated valve is employed for controlling the access of atmospheric or artificial 90 pressure to the bellows 6 through the port or passage 7. The valve chest or casing consists of a bottom plate 8 which is suitably fastened on top of the wind chest and has a port 9 communicating with the 100 port or passage 7. Ports 10 extend through the plate 8 and communicate with the space 11 which leads to the interior chamber 1. The electro-magnet 12 has its poles 13 extending through the plate 8 and their upper 105 ends exposed on the upper face thereof. A suitable circuit 14 leads to the organ key controlling the particular pipe and on the

depression of such key, the electro-magnet 12 is energized and its poles 13 become magnetic.

The parts thus far described are well known and I lay no claim thereto.

My improvement consists in the parts hereinafter set forth.

Surmounting the plate 8 and suitably connected thereto in any preferred manner is the shell or casing 15 which may be kept in proper relation to the plate by pins 16. This shell or casing has an air passage 17 which is in communication with the port 9 at one end and at its other end it is enlarged and is of circular form, as shown at 18, and centrally of said circular part is a raised and depending circular valve seat 19 with which an atmospheric port 20 communicates. The said seat has a circular knife edge 21 and a beveled or sloping circular wall 22.

The disk valve 23 is of magnetizable material and on its opposite sides is provided with facings of leather or paper 24 and 25 which are pasted or cemented thereto. The disk valve is of less thickness than the distance between the knife edge 21 and the top of the plate 8 so that it has an adaptability for movement toward the plate 8 when the electro-magnet 12 is energized. The said valve is of slightly smaller diameter than the circular guide 18 which retains and houses it in its movements.

Normally the wind pressure in the chamber 1 being in excess of the atmospheric pressure, the valve is held against its seat and the pressure from the chamber 1 passes through the ports 10 and both holds the valve against its seat and permits the wind pressure to pass into port or passage 7 and to expand the bellows 6; thus closing valve 3 and keeping valve 4 open so that the passage 2 is vented. When the key controlling the electro-magnet 12 is depressed, the magnetization of said electro-magnet attracts the disk valve and it leaves its seat and closes the ports 10 and opens port 20, whereupon the greater pressure in chamber 1, acting on bellows 6 collapses said bellows, opening valve 3 and closing valve 4, thereupon allowing the wind pressure in chamber 1 to enter passage 2 and sound the organ pipe communicating therewith. On the release of the key, the superior pressure in chamber 1 restores the parts to normal position.

Heretofore particles of foreign material, dust, etc., either from the atmosphere or the pressure wind chest, have interfered with the operation of the disk valve by getting on its face or its seat, allowing leakage and otherwise preventing accurate operation.

With my invention, actual tests have shown that this defect is remedied which is due practically entirely to the knife edge 21 of the valve seat and to the tapered or inclined wall 22 surrounding said seat. The knife edge prevents particles from lodging on the seat and the inclined wall assists in shedding them, beside which, the knife edge forms a very tight fit with the paper or leather covering of the valve. The provision of the circular valve guide obviates the necessity of providing special guiding pins or devices such as have heretofore been employed.

Having thus described my invention, what I claim as new and desire to secure by Letters Patent, is:—

1. In an electrically operated valve for pneumatic musical instruments, a valve shell having a circular concavity constituting a valve guide, a port communicating with the central portion of said concavity, a circular knife edge valve-seat rising concentrically within said concavity around said port and having an outer circular inclined wall declining from said knife edge to the bottom of said concavity, a free circular magnetizable disk valve located loosely within the circular concavity and adapted to bear against said knife edge seat, said disk valve being of but slightly less diameter than the concavity and adapted to be solely guided by the walls of said concavity when opening and closing the aforesaid port, and an electro-magnet whose poles are arranged opposite the concavity, said valve being adapted to play between said poles and said knife edge seat.

2. In an electrically operated valve for pneumatic musical instruments, a valve shell having a port, an air channel, a circular concavity constituting a valve guide, and a circular knife edge valve seat rising concentrically within said concavity having a circular inclined wall declining from said knife edge to the bottom of said concavity, said valve seat being in communication with the port aforesaid, an electro-magnet whose poles are disposed opposite the valve seat, said valve shell having a port adjacent said poles are disposed opposite the valve seat, valve located loosely within the circular concavity aforesaid and adapted to bear against said knife edge seat, said disk valve being of but slightly less diameter than the circular concavity and adapted to be solely guided by the walls of said concavity when opening and closing the ports aforesaid.

FREDERICK W. SMITH.
